A. Hanley, Jr. ATTORNEY.

UNITED STATES PATENT OFFICE.

CHARLIE M. MAYFIELD, OF BELZONI, MISSISSIPPI.

FIRE-KINDLING DEVICE.

1,411,118.

Specification of Letters Patent. Patented Mar. 28, 1922.

Application filed July 14, 1920. Serial No. 396,065.

To all whom it may concern:

Be it known that I, CHARLIE M. MAYFIELD, a citizen of the United States, residing at Belzoni, in the county of Humphreys and State of Mississippi, have invented certain new and useful Improvements in Fire-Kindling Devices; and I do hereby declare the following to be a full, clear, and exact description of the invention, such as will 10 enable others skilled in the art to which it appertains to make and use the same.

This invention relates to a fire lighting device, and the object is to provide means whereby a coal or wood fire may be lighted 15 without the use of kindling, and a device which may be repeatedly employed, and which can when finally burned out, be recharged, for further use.

A further object is to provide a device 20 of the type indicated which shall include a body of asbestos, or other suitable material, to be saturated with oil, the absorbent material being retained in compact form by enclosing the latter in a wire frame or casing, or by binding the absorbent material 25 with wire.

A still further object is to provide a device of the type indicated including an absorbent material to be charged with an 30 inflammable fluid, such as gasoline, oil, or the like, oil being preferred in the event that the device is to be used a number of times.—the article further including a handle and a coil of wire extending from 35 said handle and formed integrally therewith if desired, the coil surrounding the body of absorbent material and an element projecting from the extreme end to form a hook or the like.

40 With the foregoing and other objects in view, the invention consists in the novel construction, combination, and arrangement of elements hereinafter described and claimed.

In the accompanying drawings 45 Figure 1 is a perspective view of the device.

Figure 2 is a view in side elevation illustrating the manner in which the absorbent material is secured in place, and

50 Figure 3 is a view partly in section of the rear end of the handle.

In carrying out my invention I provide a handle which may be formed of twisted

wire, the main portion of the handle being 55 designated 10, and the free ends having connection if desired with a plate of sheet metal, having its edge portion rolled along the diverging portions 14 of the elements of the handle per se, and also rolled around the end or transverse member 16.

The body of absorbent material is preferably formed of asbestos, and is rolled into compact form and is encircled by wire 18. This wire 18 may be wound spirally as shown and may be an extension of one of 60 the wires of the handle.

A hook 20 projects from the end of the absorbent body, and may be used for such purpose as it will readily serve in connection with the use of the device in applying 70 flame to the fuel, and may also be used for supporting the article from a hook or nail, when not in use. The hook may be formed on the end of one of the wires of which the handle is formed, although I do not 75 wish to be understood as unnecessarily limiting myself to minor details of construction.

By the use of a device of this type, the flame resulting from the burning oil or gasoline, may be applied in a most efficient manner, and below the fuel to be ignited, it being usual when using oil to apply the latter from above so that the effect is only 80 partial.

85 What I claim is:—

A device of the class described consisting of a strand having parallel contacting portions, the strand from one of said portions being returned to the handle end of 90 the device and comprising a plurality of coils disposed about and in spaced relation to said portions, the free ends of the coils being secured about said portions, and the free end of one of said portions extending through and beyond the coils and terminating in a hook, and a kindling medium retained by the coils about said portions.

95 In testimony whereof I affix my signature in presence of two witnesses.

CHARLIE M. MAYFIELD.

Witnesses:

THOMAS H. HARRIS,
L. G. SEVIER.
